(57) **CLAIM**

I claim the ornamental design for a connector, as shown and described.

DESCRIPTION

FIG. 1 is a top view of a connector showing my new design; FIG. 2 is a bottom view thereof; FIG. 3 is a left side view thereof; FIG. 4 is a right side view thereof; FIG. 5 is a front view thereof; FIG. 6 is a rear view thereof; FIG. 7 is a perspective view thereof; and, FIG. 8 is another perspective view thereof. The broken lines depict portions of the connector that form no part of the claimed design.
